UNITED STATES PATENT OFFICE.

PAUL C. GIEGLER, OF RIVER FOREST, ILLINOIS, ASSIGNOR TO UNIVERSAL TOY & NOVELTY MANUFACTURING COMPANY, OF OAK PARK, ILLINOIS.

TOY.

1,410,009.

Specification of Letters Patent. Patented Mar. 21, 1922.

Application filed March 10, 1921. Serial No. 451,201.

To all whom it may concern:

Be it known that I, PAUL C. GIEGLER, a citizen of the United States, and a resident of the village of River Forest, county of Cook, and State of Illinois, have invented certain new and useful Improvements in Toys, of which the following is a specification.

My invention relates to improvements in toys, and has for its object the provision of an improved animated toy which is of simple construction, capable of economical manufacture and efficient and attractive in use.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side view of a toy embodying the invention;

Fig. 2, a top plan view of the same;

Fig. 3, a section taken on line 3—3 of Fig. 1;

Fig. 4, a section taken on line 4—4 of Fig. 2; and

Fig. 5, a view similar to Fig. 1 but showing a slightly modified form of construction.

The form of construction illustrated in Figs. 1 to 4 inclusive, comprises a suitable frame 6 preferably made of wire, as shown, and having transverse axles 7 and 7' mounted therein. The axle 7' is in the form of a double crank shaft, the cranks 8 thereof being oppositely arranged as shown. Each of said axles carries two wheels 9, the wheels on axle 7' being rigidly secured thereto so as to cause operation thereof when the toy is drawn over a floor or the like.

Animal figures 10 in the form of race horses are pivotally mounted on said frame, the rear legs of said horses carrying sleeves 11 which are loosely mounted on the rear axle 7 to oscillate freely thereon, said sleeves also serving to maintain proper lateral relations of the figures 10. The forward legs 12 of the figures 10 are pivotally connected with the cranks 8 and also carry circular heads 13 let into recesses or sockets 14 formed on the inner sides of the figures 10 and pivotally secured in place by screws 15 and whereby an operative connection is

established between the figures 10 and the cranks 8.

By this arrangement, it will be observed that as the toy is drawn over the floor or the like, the figures 10 will be caused to oscillate through the action of the cranks 8 and the legs 12, and this oscillation, in conjunction with the forward movement over the floor, will closely imitate the movements of galloping race horses, thus constituting an efficient and attractive animated toy capable of economical manufacture.

In the modified form of construction illustrated in Fig. 5, the positions of the axles 7 and 7' are reversed and the rear legs 12' of the figures 10 are attached to the cranks 70 of the rear axle 7'. The operation and visual effect is substantially the same as that already described.

While I have illustrated and described the preferred forms of construction for carrying my invention into effect, this is capable of variation and modification without departing from the spirit of the invention. I, therefore, do not wish to be limited to the precise details of the construction set forth, 75 but desire to avail myself of such variations and modifications as come within the scope of the appended claims.

Having described my invention, what I claim as new and desire to secure by Letters 85 Patent is:

1. A toy comprising a frame formed from a continuous piece of wire; two axles for said frame, one of said axles being in the form of a crank shaft; a sleeve embracing 90 the other of said axles; wheels on said axles; a figure fixedly secured to said sleeve; and legs for said figure pivoted thereto and also pivoted to the crank of said crank shaft axle, substantially as described.

2. A toy comprising a frame; two axles in said frame, one of said axles being in the form of a crank shaft; wheels on said axles; the wheels on said crank shaft being attached thereto; a sleeve loosely positioned 100 on the other axle and a figure fixedly secured to said sleeve and operatively connected with said crank shaft, substantially as described.

3. A toy comprising a frame formed from a continuous piece of wire; two axles for said frame, one of said axles being in the form of a crank shaft; a sleeve embracing

2
the other of said axles; wheels on said axles; a figure fixedly secured to said sleeve; a socket formed in said figure; and legs for said figure pivoted in said socket and also 5 pivoted to the crank of said crank shaft axle, substantially as described.

4. A toy comprising a wheeled frame; axles in said frame, one of said axles being in the form of a double crank shaft; oppositely disposed figures pivoted on the other of said axles; sockets formed in each of said figures; and legs for said figures mounted in said sockets and pivoted to the cranks of said crank shaft axle, substantially as described.

15 5. A toy comprising a wheeled frame formed from a single piece of wire; axles in

said frame, one of said axles being in the form of a double crank shaft; oppositely arranged sleeves loosely embracing the other of said axles; figures fixedly secured to said sleeves; sockets formed in said figures; and legs for said figures mounted in said sockets and also pivoted to the cranks of said crank shaft axles, substantially as described.

20 In testimony whereof I have signed my name to this specification in the presence of two subscribing witnesses.

PAUL C. GIEGLER.
